UNITED STATES PATENT OFFICE.

GEORGE D. LAWSON, OF FORT DODGE, IOWA

CARBON SCRAPER.

Application filed June 21, 1926. Serial No. 117,380.

The object of this invention is to provide an improved tool for scraping and removing accumulations such as carbon from a lateral annular groove, such as the ring groove of a piston.

A further object is to provide an improved tool of the character described which has a plurality of improved and removable and replaceable cutting bits of any convenient 10 size.

A further object is to provide a tool of the character described which is adapted for use on pistons of varying diameter.

A further object is to provide such a tool 15 comprising a spring band carrying the cutting bits and with integral handles adapted for compressing and manipulating the tool, said handles and adjacent portions of the band being concavo-convex in cross-section.

20 With these and other objects in view, my invention consists in the construction, arrangement and combination of elements hereinafter set forth, pointed out in the claims and illustrated by the accompanying 25 drawing, in which—

Figure 1 is a perspective view of the improved tool.

Figure 2 is a plan view, partly in section, 30 showing the tool in position for practical use relative to a piston.

Figure 3 is a section on the line 3—3 of Figure 2.

Figure 4 is an enlarged cross-section 35 through one of the handles, on the line 4—4 of Figure 2.

The tool as shown is composed of a one-piece band 10 formed of spring steel and open at one point, from which project integral handles 11 and 11'. The handles 11 40 and 11' are concavo-convex in cross-section, with the concave sides directed inwardly and toward each other so that the convex surfaces form a convenient grip by which the handles may be brought toward each 45 other in the hand of a user to compress the band and manipulate the tool. The concavo-convex formation extends a considerable distance in each direction around the band 10, which is plain and curved on the arc of a circle or cylinder in its central portion.

The band is adapted to engage over and around a cylindrical object such as a piston 12 and is formed with cutting bits 13, in this instance four in number, spaced apart and directed inwardly on radial lines. The cutting bits 13 are adapted to engage in an an-

nular groove such as 14 formed in the outer surface of the piston for the reception of the ordinary piston rings, in which groove there is a tendency for carbon to accumulate 60 in use. My tool is for the purpose of scraping, cutting and removing the carbon accumulations quickly and conveniently when the motor is overhauled, or at any time when the pistons are removed from the cylinders. 65 Each bit 13 is flat in the direction of the plane of the band 10 and is notched or forked at its inner end in a direction perpendicular to said plane, whereby sharp cutting edges are formed at both sides of the 70 bit. Each bit 13 is formed with a stem 15 projecting through a hole in the band 10 and secured in any suitable manner, as by riveting or by a nut 16 threaded on the stem outside of said band. 75

In practical use the band 10 is caused to embrace a piston such as 12 in the manner shown, with the bits 13 entering the groove 14. The handles 11 and 11' are then compressed within the hand of the operator and the scraping operation is consummated by a rotary oscillation imparted to the band, causing the sharp edges of the bits to bite, cut and scrape the hardened accumulations and remove the same quickly and easily without 85 injury to the piston. It is apparent that because of its spring construction, the tool does not need to be made exactly the diameter of the piston, and consequently one tool is 90 adapted for use on a variety of pistons of different diameter. The concavo-convex construction adds strength to the handles and band and makes the handles of more convenient shape for grasping in the hand. The two attenuated cutting or scraping edges of 95 each bit make for efficiency in the scraping operation, compensate for the curvature of the piston. The transverse curvature of the band preferably extends through an arc of at least ninety degrees from each of the handles 11 and 11' so that only the midportion thereof is plane transversely and capable of bending when the handles are compressed. This construction adds materially to the strength of the tool and prevents 100 undesirable bending near the points of junction of the handles when force is applied thereto in operating the tool. This curvature of the band extends well past the end bits, or those nearest the handles, and approximately to the more remote bits near the center of the band, and gradually tapers out

105 110

into or merges with the plane central portion of the band.

I claim as my invention—

1. A spring band of circular form and open at one point, integral handles at the ends of said band, cutting bits carried by said band and projecting inwardly thereof, said handles and the end portions of said band being curved transversely and the mid-
portion of the band being plane transversely to permit bending and compression of the band by pressure on said handles.

2. A carbon scraper, comprising a band of spring metal open at one point and provided with integral handles at its ends 15 adapted to be grasped in the hand of a user, and cutting bits on and projecting inwardly of said band, the handles being concavo-convex in cross-section and such curvature extending from each of said handles a considerable distance along the band and through an arc of at least ninety degrees from each end thereof.

GEORGE D. LAWSON.
